CONCRETE SUPPLY RECEPTACLE AND
HOPPER COMBINATION

Ronald M. Guntert and Wilbur F. Earley, Stockton, Calif., assignors to Guntert & Zimmerman Const. Div., Inc., Stockton, Calif., a corporation of California
Original application Mar. 18, 1960, Ser. No. 15,871, now Patent No. 3,135,178, dated June 2, 1964. Divided and this application Mar. 31, 1964, Ser. No. 356,322
2 Claims. (Cl. 94—46)

This invention relates to concrete slab laying machines of the type designed to lay wide slabs, such as are required in highway and air-strip paving and similar operations; a machine for this purpose being shown in our co-pending application Serial No. 15,871 (now Patent No. 3,135,178) and of which the instant application is a division.

The major object of the present invention is to provide such a machine with a full-width hopper which feeds the concrete directly under the concrete smoothing and depth limiting pan of the machine at the forward end of such pan, and a concrete supply receptacle mounted in connection with and above the hopper for movement along the same to feed the supply in the receptacle into the hopper in distributed amounts throughout the length of the hopper.

The receptacle is fixed on a carriage, and another object of the invention is to mount the carriage for movement lengthwise of the hopper in such a manner that the carriage and its supporting rails are maintained clear of the hopper, so that no concrete will drop on said rails, and the top of the hopper is left unobstructed, except for the receptacle, so that concrete may be dumped directly into the hopper if desired.

A further object of the invention is to provide a self-propelled carriage for the purpose, and the travel of which, in one direction or the other, may be controlled from a relatively remote point.

A still further object of the invention is to provide a practical, reliable, and durable concrete supply receptacle and hopper combination and one which is exceedingly effective for the purpose for which it is designed.

These objects are accomplished by means of such structure and relative arrangement of parts as will fully appear by a perusal of the following specification and claims.

In the drawings:

FIG. 1 is a side elevation of a concrete slab laying machine as equipped with the improved hopper and distributing receptacle associated therewith.

FIG. 2 is a somewhat enlarged foreshortened front elevation of the machine.

FIG. 3 is an enlarged fragmentary longitudinal section on line 3—3 of FIG. 2.

FIG. 4 is a fragmentary transverse section on line 4—4 of FIG. 3.

Referring now more particularly to the drawings and to the characters of reference marked thereon, the concrete slab laying machine to which the present invention is applied is indicated generally at 1. Such machine embodies a frame, denoted generally at 2, which includes transverse beams 3 and uprights 4 at the ends of such beams. The uprights 4 are secured to bolsters 5 which support self-propelled endless track units 6.

The machine 1 further embodies, and as a part of the present invention, a transverse concrete distributing hopper 7 which extends substantially the full distance between the track units 6. This hopper, which is closed at its ends, is rigidly secured to the frame 2 just ahead of the foremost transverse frame beams 3; the top of the hopper being below the top level of the upper beam 3, as shown in FIG. 3. Said hopper, which includes front

2

and rear walls 8 and 9, respectively, is open at the bottom so as to feed onto the ground and under the usual concrete confining and smoothing pan 10 of the machine.

Mounted on the machine to receive concrete from the mixer and feed the same into the hopper 7 is a receptacle 11. This receptacle has downwardly sloping sides which provide a full-length mouth 12 disposed directly over the hopper 7 a short distance above the same.

The receptacle is fixed with a carriage 13 projecting rearwardly from the same and provided with front and rear pairs of flanged wheels 14 and 15, respectively; the terms "front" and "rear" designating the relationship of the wheels to the slab laying machine lengthwise thereof.

The front wheels 14 ride on rails 16 mounted on the frame 2 transversely of the machine, or lengthwise of the hopper 7 parallel thereto and just back of and above the top of the rear wall 9 of the hopper, as clearly shown in FIG. 3.

The rear wheels 15 ride against similar rails 17 mounted on the frame of the machine above said wheels 15. By so mounting the carriage, it cannot tip forwardly and downwardly with the weight of the receptacle and its load, while at the same time the rails are out of the way of concrete being dumped into the hopper, and there is no danger of any concrete being deposited on the rails. Also, since the rails are clear of the hopper and the receptacle 11 may be moved clear of any portion of the hopper at the option of the operator, concrete may be dumped directly into the hopper at any point in its length.

The front wheels 14 are reversibly driven by chain drive units 18 connected to a reversible motor 19 mounted on the carriage 13; operation of the motor 19 being controlled by the operator of the machine—from his seat 20—through the medium of suitable electrical connections of conventional type.

By means of the above described arrangement, the receptacle 11 may be moved back and forth from one end to the other of the hopper so as to receive concrete from either side of the machine and feed the concrete in evenly distributed amounts along the hopper.

An arcuate gate 21 normally closes the mouth 12 of the receptacle 11; said gate having end ears 22, each of which overlaps the adjacent end wall of the receptacle and is pivotally connected thereto, as at 23. A sprocket wheel 24 is connected to one ear axially of the pivot 23, and is engaged by an endless chain 25 driven by a reversible motor and reduction gear unit 26 mounted on the carriage 13; said unit being controlled in the same manner as the motor 19. The gate may thus be opened to any degree desired for the proper regulated discharge of the concrete therefrom as the receptacle moves along the hopper.

From the foregoing description, it will be readily seen that there has been produced a receptacle and hopper combination such as substantially fulfills the objects of the invention, as set forth herein.

While this specification sets forth the present and preferred details of construction, still in practice such deviations from such details may be resorted to as do not form a departure from the spirit of the invention, as defined by the appended claims.

Having thus described the invention, the following is claimed as new and useful and upon which Letters Patent is desired:

1. In a concrete slab laying machine, a transversely extending elongated hopper mounted on the machine adjacent its forward end, the hopper being open at the bottom to discharge onto the ground, a concrete supply receptacle disposed above the hopper to discharge into the same, a carriage rigid with the receptacle, means mounting the carriage on the machine for movement of the receptacle lengthwise of the hopper over the same, the receptacle

having a bottom discharge opening, a closure gate for said opening, means including a pivot element rigid with the gate mounting the same on the receptacle for opening and closing movement, a remote-controlled motor and reduction gear unit mounted on the carriage, and an operative connection between said unit and the pivot to rotate the latter and thus swing the gate between open and closed positions; the carriage mounting means comprising a pair of rails on the machine spaced lengthwise thereof and disposed parallel to and extending the full length of the hopper in adjacent relationship to said hopper, wheels on the carriage, the wheels nearest the receptacle riding on the foremost rail and the wheels furthest from the receptacle riding against the underside of the rearmost rail, a remote controlled reversible motor mounted on the carriage, and drive means between the motor and certain ones of the wheels.

2. In a concrete slab laying machine, a transversely extending elongated hopper mounted on the machine adjacent its forward end, the hopper being open at the bottom to discharge onto the ground, a concrete supply receptacle disposed above the hopper to discharge into the same, a carriage rigid with the receptacle, means mounting the carriage on the machine for movement of the receptacle

lengthwise of the hopper over the same, the receptacle having a bottom discharge opening, a closure gate for said opening, and controlled means on the carriage connected to the gate to open and close the same; the carriage mounting means comprising a pair of rails on the machine spaced lengthwise thereof and disposed parallel to and extending the full length of the hopper in adjacent relationship to said hopper, wheels on the carriage, the wheels nearest the receptacle riding on the foremost rail and the wheels furthest from the receptacle riding against the underside of the rearmost rail, a remote controlled reversible motor mounted on the carriage, and drive means between the motor and certain ones of the wheels.
